UNITED STATES PATENT OFFICE.

WALTER CHIPPERFIELD, OF HORNCHURCH, ENGLAND, ASSIGNOR, BY MESNE ASSIGNMENTS, TO A. B. DICK COMPANY, OF CHICAGO, ILLINOIS, A CORPORATION OF ILLINOIS.

SHEET-FEEDING MECHANISM OF PRINTING AND LIKE MACHINES.

Application filed April 18, 1921. Serial No. 461,016.

To all whom it may concern:

Be it known that I, WALTER CHIPPERFIELD, a subject of the King of Great Britain, residing at Kinkora, Great Nelmes, 5 Hornchurch, Essex, England, have invented certain new and useful Improvements in Sheet-Feeding Mechanism of Printing and like Machines (for which I have filed an application in Great Britain January 19, 10 1920, No. 1,646, Patent No. 162,052), of which the following is a specification.

My invention relates to improvements in type printing, duplicating and like machines and has special reference to means 15 for insuring registration of sheets of paper when fed through the machine either by hand or by automatic means.

In machines of this class as previously manufactured there have been employed two 20 feed rollers which grip each sheet of paper fed thereto, and carry the same between the impression roller and the printing cylinder. These feed rollers have hitherto, in the constructions with which I am familiar, been 25 so arranged that continuous motion has been imparted to them. In this prior construction, one of these rollers has been acted upon by a mechanism which permits contact of the gripping surfaces of the rollers 30 to be broken sufficiently to allow a sheet of paper to pass between the same, without disturbing the rotation of the rollers. A paper gauge has also been employed against which the forward edge of a sheet engages 35 after passing through the opening between the two feed rollers, and at a certain point during the rotation of the printing cylinder the feed rollers are caused to grip the sheet of paper, and the gauge device has 40 been removed from the path of the paper, and the sheet fed forward by the feed rollers between the impression roller and printing cylinder.

With such machines the continual rotation of the feed rollers presents certain disadvantages in that when these rollers close together to grip a sheet there is a tendency for the proper registration of the sheet to be rendered uncertain.

50 In the present invention means are provided whereby the feed rollers are only caused to rotate after they have gripped the sheet, at the time when the sheet is about to be presented to the impression roller and

the printing cylinder. By this means a 55 much better registration of the sheet will be obtained, than in the prior constructions referred to.

In order that a clearer understanding of my invention may be had, attention is hereby directed to the accompanying drawings forming part of this application and illustrating one embodiment of my invention. In the drawings Fig. 1 represents a front elevation of a printing or duplicating machine equipped with my invention, Fig. 2 is a detail view of some of the parts appearing in Fig. 1, showing the feed roller driving means, and Fig. 3 is a view similar to that shown in Fig. 2, on an enlarged scale, 70 certain parts being omitted, and the feed roller driving means being shown operatively connected for rotation.

Referring to the drawings, the printing cylinder 1 may be mounted on a suitable 75 shaft supported between the side standards 3. Secured to the cylinder is a spur gear 4, and motion is imparted to the cylinder by the handle 5 on crank 6 rotating on spindle 7, pinion 8 secured on spindle 7 engaging 80 the pinion 9 which rotates with the cylinder.

Mounted on a stud or pin 10 is a lever 11, hereafter termed a throwout lever. This lever has, as illustrated, three arms, one of 85 the same 11^a carrying stud 12 at its upper end. Pinion 13 is mounted on this stud and engages the gear 4 of the printing cylinder during the printing action.

Secured to the boss of pinion 13, and rotatable therewith, is a disc 14, and this disc carries a pair of rollers 15, 15^a which are movable with the disc and are adapted to act upon a cam surface or track 16 formed on or secured to one of the cylinder walls. 95 Pinion 13 engages at all times a pinion 17 secured on a spindle 18 which is coaxial with pins 10, spindle 18 having its ends bored out to receive and rotate upon the pins 10, in the two side frames 3.

100 Spindle 18 carries the top feed rollers 19 and pinion 17 is adapted to engage a pinion 20 secured on a spindle 21 which is carried in open bearings, in the embodiment of my invention illustrated, formed in arms 22, 105 these latter being secured on a shaft 23 which is supported by the side frames 3 of the machine. Springs 23^a are secured to

arms 29 at their lower ends and at their upper ends to screws or studs secured in the side frames 3, these springs tending to hold pinion 20 in engagement with pinion 17.

5 One of the bearings for spindle 21 is provided with a projection 24 which is adapted to be acted upon by a roller 25 carried by one of the arms 11^b of the throw-out lever 11. Mounted upon spindle 21 are the lower 10 feed rollers 26.

The gauge device for the paper comprises a rod 27 carried by the side standards 3, this rod having fingers 28 thereon which in their operative position project upwardly 15 behind the adjacent surfaces of rollers 19 and 26, as shown in Fig. 2. Rod 27 carries an arm 29, controlled by a spring 30, the other end of the spring being secured to a pin or stud secured to one of the side standards 3, this spring tending to hold fingers 28 in the raised position shown in Fig. 2. Rod 27 also carries a trip arm 31 which is adapted to be acted upon by the end of screw 32 which is adjustably mounted in a 20 lug formed adjacent to the bottom end of lever 11, engagement of pin or screw 32 with arm 31 resulting in the lowering of fingers 28. A spring 33 is secured to the lower end of lever 11, the other end of the spring being secured to a frame member 3 of the 25 machine, the tendency of this spring being to press pinion 13 towards the gear 4, the three arms referred to of lever 11 swinging about the axis of spindle 18 as a centre.

30 In operation, during the time a sheet of paper is being printed, the spur gear 4 of the printing cylinder is in mesh with the pinion 13, as is shown in Fig. 3, rotation being communicated through pinions 13, 17 and 20 to the feed rollers 19 and 26. Trip arm 31 has been acted upon by screw 32 to lower fingers 28 out of the path of sheets fed between feed rollers 19 and 26, and the sheet of paper is fed by the feed rollers between the impression roller and printing cylinder, for printing.

On further rotation of the printing cylinder the rollers 15 and 15^a carried by disc 14 ride on the cam surface or track 16, as 50 is shown in Fig. 2. This causes a rocking motion to be imparted to lever 11 so that pinion 13 carried thereby is disengaged from spur gear 4 and the rotation of feed rollers 19 and 26 immediately ceases. At the same time arm 11^b of lever 11^a swings downwardly to cause roller 25 to press upon projection 24, so that spindle 21 is pressed downwardly, against the spring 23^a, this effecting a separation of the feed rollers 26 from rollers 19.

60 The swinging of the throw-out lever referred to also moves pin 32 away from trip arm 31 and permits rod 27 to be rotated by spring 30 so as to bring fingers 28 into their upper or operative position behind and slightly above the point of contact of feed

rollers 19 and 26 as is shown in Fig. 2. In this position, the feed rollers being separated and at rest, the sheet of paper is fed forward between the feed rollers until its forward edge registers against fingers 28. 70

On further rotation of the printing cylinder the rollers 15, 15^a drop down on to a recessed portion of the cam or track 16^a. This action causes sufficient movement of the throw-out lever 11 to bring the two feed 75 rollers 19 and 26 together, the sheet of paper being gripped thereby, but these rollers still remain stationary inasmuch as the rocking motion of the throw-out lever has been insufficient to cause the pinion 13 to mesh 80 with spur gear 4.

Further movement of the printing cylinder causes the roller 15 to ride off the recessed surface 16^a. Further movement is now afforded to the throw-out lever 11, so 85 that the spring 33 causes pin 32 to strike against trip arm 31 to rock rod 27 and cause fingers 28 to be lowered. Further movement of the cylinder causes the roller 15^a to ride clear of the cam or track whereupon 90 the pinion 13 again meshes with spur gear 4, feed rollers 19 and 26 are set in motion, and the sheet of paper is fed by them between the impression roller and the printing cylinder. 95

It should be understood that my invention is not limited strictly to the details of construction described but is as broad as is indicated by the accompanying claims.

What I claim is:—

1. In sheet feeding mechanism, the combination of feed rollers, a printing cylinder, means tending to press said rollers together, a gear train for rotating said rollers during a part of the rotation of said cylinder, and means for disconnecting said gear train to stop the rotation of said rollers during another part of the rotation of said cylinder. 105

2. In sheet feeding mechanism, the combination of feed rollers, a printing cylinder, means tending to press said rollers together, a gear train for rotating said rollers during a part of the rotation of said cylinder, and means effective during another part of the rotation of said cylinder, for disconnecting said gear train and separating said rollers from each other. 115

3. In sheet feeding mechanism, the combination of feed rollers, a printing cylinder, a gear on said cylinder, a pivotally mounted pinion, means tending to press said pinion into mesh with said gear to drive said rollers, a cam disk rotatable with said pinion, and means including a cam surface carried on said cylinder and engaging said cam disk during a portion of the rotation of said cylinder for moving and holding said pinion out of mesh with said gear. 120

4. In sheet feeding mechanism, the com- 130

bination of feed rollers, a printing cylinder, a gear on said cylinder, a pivotally mounted pinion, means tending to press said pinion into mesh with said gear to drive said 5 rollers, a cam disk rotatable with said pinion, and means including a cam surface carried on said cylinder and engaging said cam disk during a portion of the rotation of said cylinder for moving and holding 10 said pinion out of mesh with said gear and for holding said pinion against rotation on its axis.

5. In sheet feeding mechanism, the combination of feed rollers, a printing cylinder, 15 a gear on said cylinder, a pivotally mounted pinion, means tending to press said pinion into mesh with said gear to drive said rollers, a cam disk rotatable with said pinion, means including a cam surface carried on 20 said cylinder and engaging said cam disk during a portion of the rotation of said cylinder for moving and holding said pinion out of mesh with said gear and for holding said pinion against rotation on its axis, a 25 gauge member, connections between said gauge member and said cam disk, and means comprising a second cam surface carried on 30 said cylinder and engaging said cam disk during another portion of the rotation of said cylinder for moving said gauge member out of the path of a sheet passing between said rollers and for holding said pinion out of mesh with said gear and against rotation about its axis.

35. 6. In sheet feeding mechanism, the combination of a printing cylinder, a gear and cam rotatable therewith, a pair of feed rollers, an arm pivoted on the shaft of the upper roller, a pinion on said arm, adapted 40 to mesh with said gear, a pinion on said upper roller meshing with said first pinion, means for rotating the lower roller from the upper roller, and means carried by said arm,

engaged by said cam for a portion of the revolution of said cylinder, for moving said 45 first pinion out of mesh with said gear.

7. In sheet feeding mechanism, the combination of a printing cylinder, a gear and cam rotatable therewith, a pair of feed rollers, a movable bearing for the lower 50 roller, an arm pivoted on the shaft of the upper roller, a pinion on said arm, adapted to mesh with said gear, a pinion on said upper roller, meshing with said first pinion, means for rotating the lower from the upper 55 roller, means carried by said arm, engaged by said cam for a portion of the revolution of said cylinder, for moving said first pinion out of mesh with said gear, and an arm movable with said first arm, as the latter swings 60 away from said gear, for engaging against said movable bearing for separating said rollers.

8. In sheet feeding mechanism, the combination of a printing cylinder, a gear and 65 cam rotatable therewith, a pair of feed rollers, an arm pivoted on the shaft of the upper roller, a pinion on said arm, adapted to mesh with said gear, a pinion on said upper roller, meshing with said first pinion, 70 means for rotating the lower roller from the upper roller, a gauge member, means, carried by said arm, engaged by said cam for a portion of the revolution of said cylinder, for moving said first pinion out of mesh 75 with said gear, means for at the same time holding said gauge member in the path of a sheet passed between said rollers, and a member movable with said arm, when said first pinion returns into mesh with said gear, to press said gauge member out of the path of a sheet passing between said 80 rollers.

This specification signed and witnessed this 18th day of March, 1921.

WALTER CHIPPERFIELD.
